METHOD FOR MAKING COMPOSITION
FIBER PANELS

Carl Blecko, Preston, Wash., assignor to Rockwood Corporation, Issaquah, Wash., a corporation of Washington

Application July 26, 1948, Serial No. 40,714

3 Claims. (Cl. 25—155)

1

The present invention relates to a method for producing fiber board.

It is an object of the present invention to produce a fiber board comprising a cemented fiber body portion and a coating therefor containing plaster, wheat paste, sugar, bentonite, and asbestos.

It is a further object of the present invention to provide a method for producing a fiber board constructed and arranged to provide increased productivity in the production of the board.

It is a further object of the present invention to provide a method of making fiber boards which comprises advancing a supply of fluid fiber-cement mix along an inclined path, providing working stations of different height along said path, providing a horizontal conveyor parallel to said path, in which operators are provided at each station to fill forms and place them upon a top of a stack of forms advanced from a preceding station of less height.

Other objects and features of the invention will become apparent as the description proceeds, especially when taken in conjunction with the accompanying drawings, wherein:

Figure 1 is a more or less diagrammatic side elevation of apparatus employed in the production of fiber board.

Figure 2 is a fragmentary plan view of the apparatus illustrated in Figure 1, and

Figure 3 is a fragmentary view partly in section and partly broken away of a stack of forms.

In accordance with the present invention, fiber board is produced by forming relatively long wood fibers, impregnating the fibers with salt by soaking them in a salt solution, thereafter draining excessive moisture from the fibers, thoroughly mixing the fibers with Portland cement, and finally placing the resulting fluid mix in open topped forms or molds. Special means are provided to facilitate the operation of filling the forms and for assembling the filled forms in vertical stacks or tiers. After a predetermined number of forms have been assembled in vertically stacked relation they are advanced into a press. The individual forms are so shaped that when pressure is applied thereto they will be compressed together a predetermined amount so as to produce fiber boards of a uniform standard thickness. After pressure has been applied in a press the stack of forms is secured together and is allowed to set.

Subsequently, the boards are removed from the molds and are coated with a combination consisting of an aqueous mixture, the solid constituents of which are wheat paste, sugar, ben-

2

tonite, and asbestos. This coating material is in the form of a paste which is spread to a uniform thickness on one or both surfaces of the fiber board after which the fiber board is baked preferably by exposure to infra-red radiation. Finally the complete fiber board is sawed to desired dimension after which it is permitted to air dry for several days.

Referring now to the drawings, the apparatus employed in the production of the fiber boards is preferably installed in a two story building. Located on the first floor of the building is a fiberizing machine indicated at 10 in which wood is reduced to a fibrous state. Machines suitable for this purpose are readily available and it will not be described in detail. However, it may be noted that preferably the wood supplied to the machine for fiberizing is cut into eighteen inch lengths, thus to a large degree predetermining the length of fibers produced.

Suitable means such for example as a blower (not shown) are provided for blowing the fibers through a conduit 11 into a tank 12 which is located on the second floor of the building. The tank 12 contains a solution of common salt and the fibers are permitted to stand in the salt solution until thoroughly impregnated. Thereafter, the fibers are removed from the salt solution in the tank 12 and the excess water is permitted to drain off. The damp fibers are then placed in an elongated tank 14 which is provided with a plurality of rotating metal paddles indicated generally at 15. Overlying one end of the tank 14 is a hopper 16 which contains dry Portland cement which is sifted onto the fibers by suitable means such for example as a worm screw (not shown), driven at a rate to supply the appropriate amount of cement.

The paddles 15 rotate in the direction of the arrow shown in Figure 1 and have a dual purpose. In the first place, they insure thorough mixing of the dry cement with the damp fibers so that in effect each of the fibers is substantially completely coated with cement. At the same time the paddles advance the fiber coated cement longitudinally of the tank 14.

At the discharge end of the tank 14 there is a downwardly opening passage 18 connecting to an inclined open topped chute 19. By the time the cement coated wood fibers reach the chute 19 they form a semi-fluid mass which may advance downwardly along the chute 19 by gravity, or if preferred the chute may include a conveyor for advancing the material at a predetermined rate downwardly along the chute.

Adjacent the chute are a plurality of work-

ing stations designated 20, 21, 22 and 23. The stations are of progressive height in accordance with the inclination of the chute and provide a platform on which a workman may stand and have convenient access to the material being advanced downwardly along the chute.

Paralleling the line of working stations 20-23 is a conveyor system which may take the form of a plurality of rollers along which suitable frames are advanced.

In operation a workman is located at each of the stations 20-23. Open topped forms or molds 25 are provided and each of the workmen places a predetermined amount of cement coated fibers in a predetermined number of forms and assembles the forms in vertical stacks or tiers. Thus for example, in the present embodiment of the invention illustrated it is contemplated that four working stations will be provided and that at each station the workman will fill and stack five molds. When the workman at station 20 has completed filling and stacking five molds he pushes the stack of molds to the station 21 at which station the second workman fills and adds five more molds or forms to the stacks. This operation is continued until at station 23 the workman completes the stack of twenty forms by filling and adding five forms thereto. Thereafter the assembly of stacked forms is advanced to a press 30 at which point sufficient pressure is supplied to the assembly of forms to cause all of the forms to interfit as illustrated in Figure 3. It will be observed that each of the molds is adapted to interfit with the adjacent molds so that when sufficient pressure is applied to bring each of the molds into engagement with the adjacent molds, the contents of the molds will be compressed to a uniform predetermined thickness. In practice it is contemplated that the forms will be of a size to produce fiber board having a thickness of one inch or three inches although of course any desired thickness of board may be produced by the selection of proper molds.

After the assembly of molds has been compressed so as to bring each of the molds into contact with the adjacent molds, suitable means are provided to retain the assembly of stacked molds in compressed relationship. This means is illustrated in Figure 3 as comprising a plurality of rods 35 having nuts 36 by means of which clamping members 37 may be secured together in the manner illustrated.

After the forms have been bound together they are removed from the press with a lift truck and are allowed to stand for at least twenty-four hours which permits the cement to set and causes the boards to reach a condition in which they will retain their shape.

Thereafter the boards are removed from the forms and are placed on a conveyor belt one at a time and a smooth coating of paste is applied to one side of the boards. This paste in its preferred form has solid constituents which are by weight approximately eighty-two per cent plaster, five per cent wheat paste, five per cent sugar, three per cent bentonite filler and five

per cent asbestos. The solid constituents are mixed with water to form a paste of a consistency suitable for spreading as by means of a doctor blade or the like. In practice the conveyor belt advances the board beneath the doctor blade which provides a predetermined coating of paste, after which the same conveyor advances the boards through a tunnel with means therein for drying the coating hard enough so that the boards may be trimmed. Preferably electric heating means are provided in the tunnel and this means may conveniently take the form of sources of radiant heat. The parts are constructed and arranged so that upon emergence from the tunnel the coating is hard enough to permit trimming the boards. Thereafter the boards are advanced to a trimming saw which cuts them to desired dimensions. Finally, after cutting the boards are stacked up to air dry for three or four days before use.

The drawings and the foregoing specification constitute a description of the improved composition wood panel and method and apparatus of making same in such full, clear, concise and exact terms as to enable any person skilled in the art to practice the invention, the scope of which is indicated by the appended claims.

What I claim as my invention is:

1. The method of making sheet material from a fluid mix which comprises advancing fluid mix along an incline, advancing a form for receiving fluid mix substantially horizontally in a vertical plane substantially parallel to a vertical plane through the fluid mix traversing incline, during progress of such form lengthwise of the fluid mix incline adding successively thereon additional forms in stacked relationship, the height of the stack of forms thereby being increased as such stack progresses toward the higher end of the fluid mix incline, and prior to the addition of each form to the stack placing in each top form fluid mix from such incline.
2. The method defined in claim 1, including advancing the stack of forms intermittently and supplying mix to the top form on the stack while the stack is stationary.
3. The method defined in claim 1, including adding a plurality of forms to the stack each time it is stopped during its progress lengthwise of the fluid mix incline.
